UNITED STATES PATENT OFFICE.

FREDERICK TRINCA AND HENRY WOLF, OF NEW YORK, N. Y., ASSIGNORS TO EVER READY AUTO SIGNAL CO., INC., OF NEW YORK, N. Y., A CORPORATION OF NEW YORK.

DESIGN FOR A STOP SIGNAL AND TAIL-LIGHT LENS.

Application filed March 20, 1922. Serial No. 1,257. Term of patent 14 years.

To all whom it may concern:

Be it known that we, FREDERICK TRINCA and HENRY WOLF, citizens of the United States, residing at New York, in the county of New York and State of New York, have invented a new, original, and ornamental Design for Stop Signal and Tail-Light Lens, of which the following is a specification, reference being had to the accompanying drawing, forming part thereof.

Figure 1 is a front plan view of a stop signal and tail-light lens, showing our new design,

Figure 2 is a rear plan view of the same.

We claim:—

The ornamental design for a stop signal and tail-light lens, as shown.

FREDERICK TRINCA.
HENRY WOLF.
